Primary Examiner—Gary D. Watson

(57) **CLAIM**

The ornamental design for a seat, as shown and described.

DESCRIPTION

FIG. 1 is a front elevational view of a seat showing my new design;

FIG. 2 is a left side elevational view of the seat shown in FIG. 1, the right side view is a mirror image;

FIG. 3 is a rear elevational view of the seat shown in FIG. 1; and,

FIG. 4 is a top plan view of the seat shown in FIG. 1. The broken line showing of leg members is for illustrative purposes only and forms no part of the claimed design.
